2 SHEETS—SHEET 2.

UNITED STATES PATENT OFFICE.

WILLIAM A. WHITNEY, OF ROCKFORD, ILLINOIS.

SCREW PUNCH.

1,403,866.

Specification of Letters Patent. Patented Jan. 10, 1922.

Application filed February 12, 1920. Serial No. 353,100.

To all whom it may concern:

Be it known that I, WILLIAM A. WHITNEY, a citizen of the United States, residing at Rockford, in the county of Winnebago and State of Illinois, have invented a new and useful Screw Punch, of which the following is a specification.

This invention relates to the class of metal working tools and more particularly to an improved ball bearing screw punch for punching holes in sheet metal or the like of various thicknesses and by means of which a maximum degree of pressure can be obtained with a minimum exertion of power.

It is also an object of the invention to provide an improved screw punch in the form of a tool of a portable type having a head or casting provided with a handle so as to be placed conveniently on the work and which is so constructed as to withstand great pressure when the punch is operated to produce an aperture in the material.

A still further object of the invention is to provide an improved ball bearing mounting for the feed screw of the punch, which punch is also provided with a novel form of detachable bit or point permitting renewal of the point without requiring renewal of the entire bit or shank portion thereof, and which will permit the bit to be renewed with facility.

A still further object of the invention is to provide an improved actuating means for the feed screw which will serve to support the bit in an adjusted position against its normal tendency to move downwardly by reason of its ball bearing mounting and which will permit convenient reversal of the movement of the bit so as advance or retract the same when the hole has been formed, the construction being such as to permit the retraction to be quickly effected.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 is a side elevation of my improved screw punch, partly in section.

Figure 2 is a plan view, partly in section.

Figure 3 is a horizontal sectional view taken on the line 3—3 of Figure 1.

Figure 4 is a side elevation of the standard or shank of the punch.

60

Figure 5 is a detail fragmentary horizontal sectional view taken on the line 5—5 of Figure 4.

Figure 6 is a detailed horizontal sectional view of the drill taken on the line 6—6 of Figure 4, and

Figure 7 is a vertical sectional view taken on the line 7—7 of Figure 2.

Referring to the drawings in detail, the numeral 10 designates the body of the punch 70 which is semi-circular in outline, looking at the side thereof, the edge portion 11 being relatively narrow while the body is extended at opposite sides adjacent to the axis thereof as shown at 12 in order to provide a thickened 75 portion horizontally and transversely across which there is provided a recess or slot 13 providing upper and lower jaws 14 and 15. Horizontally through the body in alignment with the recess is an opening 16 having bosses 80 17 upon opposite sides thereof at the edge portion 11 and extending radially to the thickened portion 12 so as to reinforce the edge portion at the opening 16, where the lower end of the handle 18 is turned in- 85 wardly and engaged in said opening there to be held by a set screw 19 engaged through the threaded aperture in one of said bosses and contacting with said handle end. The handle extends in an arc at a spaced dis- 90 tance and substantially concentric to the edge of the body in an upward direction the free end thereof being brought into contact with said edge where it is further limited against movement so as to bear the 95 necessary strain to permit the device to be transported to the place of use.

Adjacent to the upper extremity of the handle is a cylindrical enlargement 20 which forms a shoulder for contact by the free end 100 of said handle, said enlargement being provided with successively reduced portions 21 and 22 and a threaded extremity 23. The reduced portion 21 is designed to receive a pinion 24 which is received between the 105 spaced jaws 25 of the socket portion of a ratchet lever 26, there being mounted between the jaws 25 at the crotch of the slot thus formed, a double ended pawl 27 having projecting ends thereon parallel to its pivot 110

28 which is detachably engaged in the opposed jaws, and an oppositely beveled projection 29. The handle socket is counterbored as shown at 30 and receives therein a spring pressed and oppositely beveled sliding bolt 31 adapted to cooperate with the projection 29, said bolt being counterbored at its inner side to receive an expansible coiled spring 32 which seats against the bottom of the counterbore 30, while mounted between the opposite end of the spring and the end wall of the counterbore of the bolt 31 is a ball bearing 33 which permits free turning of the bolt and serves to take up wear. It will also be seen that since the pawl 27 is designed to rock on the pivot 28, the projection 29 will engage the oppositely beveled end or faces of the bolt 31 so as to depress the latter, after which said projection will ride over the bolt and the bolt will then be projected by its spring to retain the pawl at either side, in abutment with the end as well as the ball bearing 33 between the jaws 25. It should be noted that one of the jaws 25 has its free end cut concentric with an opening 34 therethrough as shown at 35, the other jaw being extended and providing a larger smooth-bored or unthreaded opening 36, the opening 34 being smooth-bored also. The pinion 24 is provided with circular projection 37 at the bottom thereof adapted to engage an opening 38 in the detent member comprising a plate 39 in the form of a washer having a projection 40 at one side thereof which is formed or stamped with a laterally projecting finger piece or handle 41. Projecting upwardly from the projection 40 of the plate 39 are a pair of detents or lugs 42 having the major portions thereof opposing each other and provided with a circular contour as shown at 43, their outer portions beveled or flattened as shown at 44 for a purpose to be hereinafter more fully specified. The top of the pinion 24 is counterbored and internally threaded as shown at 45 thereby providing an outwardly facing shoulder 46 which is engaged by the inner end of an externally threaded plug or nut 47 mounted on the reduced portion 22, said nut having a circumscribing flange or externally threaded inner end for this purpose and an outer wrench engaging portion, while the bore is smooth to freely turn on the reduced portion 22. A tap 48 is mounted on the threaded end 23 so as to retain the parts in position and against displacement.

At the straight vertical edge of the body there is provided a cylindrical portion 49 which is internally threaded to receive the external threads of a sleeve 50, said sleeve being provided with internal threads 51 forming a ball race in co-action with a similar spiral or threaded groove 52 which jointly forms a race way or ball race of hexagonal or other desired polygonal cross sec-

tion so that the ball bearings 53 engaged therein will contact by the plurality of points on the peripheries of the ball instead of throughout the surfacial area thereof so as to reduce friction and wear on the parts. The spiral groove 52 is formed in a drill or shank 54 which is further provided with a vertical axial passage 55 communicating with said groove through the medium of a radial passage 56 extending radially from the groove to the passage 55 at the upper end and downwardly sloping radial passage 57 at the lower portion of said drill or shank so that the drill is mounted to freely turn and will be descended of its own weight were it not held by the actuating mechanism partly described and to be hereinafter further set forth. It will also be apparent that as the drill is fed downwardly the ball bearings will be caused to circulate upwardly in the axial passage and downwardly in the spiral race way, while circulation will take place in the opposite direction when the drill is being raised. In order to deflect the balls into the race or into the radial passages and consequently into the axle passage deflectors 58 are provided facing said spiral grooves or race ways at the outer end of each radial passage, and the upper end of the drill is provided with a hexagonal or other polygonal cross section 59 above which the shank is threaded and reduced as shown at 60 to receive a flanged nut 61.

The sleeve 50 projects above the cylindrical portion 49 and is splined or keyed therein as shown at 62, the upper end of the sleeve being provided with diametrically disposed recesses 63 by which it may turn home or be removed. There is mounted on the projecting portion of the sleeve a spanner ring 64 beneath which is received a ring 65, the rings having co-acting beveled portions 66 and a packing ring or washer 67 being disposed between the upper edge of the sleeve to the ring 65. Mounted on the hexagonal portion 59 which is of reduced size relatively to the threaded portion of the drill or shank is a spur gear 68 having a projection 69 raising against the spanner ring and accommodating beneath the gear, the detent plate heretofore described, while the free end of the upper jaw of the actuating lever overlies the peripheral portion of the gear which is also formed with a projection 70 for this purpose, it being understood that the gear is provided with an opening of a cross section corresponding to that of the shank at the portion 59 in order to cause the gear to rotate the shank when driven. For this purpose, the lever is actuated and while being oscillated the detents or lugs 42 will alternately engage the teeth of the gear and resist the tendency of the parts to rotate in an opposite direction. The double ended pawl will serve to reverse the direction of

operation by engagement with the intervening notches of the pinion, so that the drill can be advanced or retracted. In addition, there is engaged or provided for engagement 5 on the nut 47 at its wrench engaging portion, a socketed wrench or crank handle 71 which may be employed for reversing the operation by throwing the pawls and detent out of operation, thus obviating the necessity for oscillating 10 the operation lever in order to reverse the position of the parts after a sheet of metal or material has been punched.

The lower end of the sleeve 50 terminates short of the lower end of the cylindrical portion, being disposed to engage an upwardly facing shoulder 72, the front portion of the cylindrical portion being recessed as shown at 73 and provided with engaging lugs 74 at either side thereof projecting downwardly 15 for contact with the upper ends of a sheet of metal to be punched. It is to be understood that the metal is received between said lugs over the lower jaw of the device and held in position during the punching operation by 20 the pressure exerted during said operation by a bit or point 75. In the preferred construction, the lower end of the shank or punch is provided with a counterbore or socket 76 for receiving said bit, the latter 25 being made detachable so that it can be renewed economically without the necessity of renewing the entire shank. For this purpose the bit is notched at its upper portion and provided with an external or circum- 30 scribing groove 77 adapted to aline tangential grooves 78 forming key ways for receiving the leg portions of the substantially U shaped key 79, the bright portion 80 of which is seated in a recess 81 in the periphery of 35 the shank or drill or drill-head or stock so as to permit the latter to move into the shell while at the same time retaining the bit or point against displacement.

Immediately below the cylindrical portion 49 the lower jaw of the body is provided with a vertical aperture 82 through which the stampings are forced and co-acting with the drill bit is an annular platen 83 which seats in a counterbore 84 in the 45 upper portion of the lower jaw concentric to said aperture. This platen is provided with a circumscribing arcuate groove 85 and mounted at the inner wall of the counterbore in a recess 86 is a spring pressed ball 50 87 which snaps into said groove and retains the platen in position while permitting it to turn. A spring 88 will give to permit this, thereby permitting the platen to be applied or removed with facility, thereby permitting 55 convenient renewal when desired or necessary, as well as obviating the objection to the use of a set screw, heretofore of common use. Thus, when the bit is brought into forced engagement with the material to be 60 punched oscillation of the operating lever 65

will steadily force it from the material during such action under pressure and the ball bearings will take up undue friction and prevent injury to the parts. The function cleavage will also take place by reason of the 70 co-action and bit and the sharpened or shouleder upper edge of the platen as is clearly shown in the drawings.

In order to cause automatic shifting of the detents, the plate thereof is provided with 75 a depending lug 89, the lower edge thereof being oppositely beveled and designed to engage a correspondingly formed upper end of the spring pressed dog 90 mounted in the top of the casting or body and adapted to be 80 depressed as the lug rides over the same during the oscillation of the operating lever or upon actuation of the plate through the medium of its finger-piece in order to reverse 85 the direction of operation so that the drill may be moved to operative or inoperative position as desired.

The lower end of the axial passage, which latter is forced out from the bottom, is closed by a plug 55'. Also by shifting the double 90 pawl 27, the lever may be oscillated to rotate the pinion in opposite directions, and the plate 39 may be secured by the finger-piece 41 to cause the detents 42 to act at opposite sides of the gear 68 to prevent reverse 95 rotation thereof under pressure or otherwise. Of course, the dog 90 will permit automatic disengagement of the detents 42 at either side from between or behind the teeth of the gear, free of the same and the pinion, as the 100 lever is actuated or oscillated, while coacting with the lug 89 at their inclined or beveled sides as shown in Figure 7 of the drawings to retain the operative detent 42 in engaged position, while the other detent is out 105 of engagement with the gear. The device will permit great pressure with ease and thick plates of metal may be punched quickly and with facility.

Having thus described the invention what 110 is claimed is:—

1. A portable screw punch comprising a flat body adapted to be disposed on edge, a handle on the edge portion of the body near the top thereof, said body being recessed to provide upper and lower jaws, the lower jaw being provided with a vertical aperture and the upper jaw being formed with a cylindrical portion of larger diameter than said aperture, and alining vertically therewith, the lower jaw having a counterbore around the aperture, a ring-like platen mounted therein and provided with a circumscribing groove, a spring pressed ball mounted in the wall of the counterbore 115 and detachably engaging said groove, a sleeve mounted in the cylindrical portion, said sleeve being provided with an internal spiral groove, a punch bit having a standard provided with a similar external 120 125 130

groove and an axial passage communicating with the upper and lower ends of said groove, ball bearings in said grooves and adapted to circulate through said passage upon rotation of the standard in either direction to raise or lower the bit, and means for rotating said standard.

2. A portable screw punch comprising a flat body adapted to be disposed on edge, a handle on the edge portion of the body near the top thereof, said body being recessed, to provide upper and lower jaws, the lower jaw being provided with a vertical aperture and the upper jaw being formed with an enlarged portion of larger diameter than said aperture and alining vertically therewith, the lower jaw having a counterbore around the aperture, a ring-like platen mounted therein and provided with a circumscribing groove, a spring pressed ball mounted in the wall of the counterbore and detachably engaging said groove, a sleeve mounted in the enlarged portion, said sleeve being provided with an internal spiral groove, a drill bit having a standard provided with a similar external groove and an axial passage communicating with the upper and lower ends of said groove, ball bearings in said grooves adapted to circulate through said passage upon rotation of the standard in either direction to raise or lower the bit, a gear mounted on said standard, a pinion rotatably supported by the body in mesh with said gear, a ratchet lever associated with said pinion for stepping the same in opposite directions, and means for reversing said ratchet mechanism.

3. The combination with a body having upper and lower jaws, the lower jaw being provided with an aperture, an annular platen mounted therein and provided with an internal cutting edge, a portion above said aperture having a recess in the front thereof and spaced depending lugs at either side of said recess, and a punch bit cooperating with said platen and movably mounted in said shell.

4. The combination with a body having upper and lower jaws, the lower jaw being provided with an aperture, an annular platen mounted therein and provided with an internal cutting edge, an enlarged portion above said aperture, a spindle mounted for spiral movement in the enlarged portion, means to depress or retract the same, said spindle having a bit at its lower end cooperating with said platen, a gear mounted on the upper end of the spindle, a pinion rotatably supported in mesh with the gear, an actuating lever straddling the pinion, a double ended spring pressed pawl carried by the lever and engaging the pinion at either side, and means for reversing the actuating direction of the lever.

5. The combination with a body having

upper and lower jaws, the lower jaw being provided with an aperture, an annular platen mounted therein and provided with an internal cutting edge, an enlarged portion above said aperture, a spindle mounted for spiral movement in the enlarged portion to depress or retract the same, said spindle having a bit at its lower end cooperating with said platen, a gear mounted on the upper end of the spindle, a pinion rotatably supported in mesh with the gear, an actuating lever straddling the pinion, a double ended spring pressed pawl carried by the lever and engaging the pinion at either side, a plate pivoted on the axis of the lever and having spaced detents co-acting with the gear to retard the movement thereof in either direction, and means for shifting said plate.

6. The combination with a body having upper and lower jaws, the lower jaw being provided with an aperture, an annular platen mounted therein and provided with an internal cutting edge, an enlarged portion above said aperture, a spindle mounted for spiral movement in the enlarged portion to depress or retract the same, said spindle having a bit at its lower end cooperating with said platen, a gear mounted on the upper end of the spindle, a pinion rotatably supported in mesh with the gear, an actuating lever straddling the pinion, a double ended spring pressed pawl carried by the lever and engaging the pinion at either side, a plate pivoted on the axis of the lever and having spaced detents and co-acting with the gear to retard the movement thereof in either direction, a finger-piece on the plate, a lug depending from the plate intermediate of said detents and oppositely beveled, and an oppositely beveled spring pressed dog cooperating with said lug to automatically shift said plate upon oscillation of the lever to temporarily retain the same in shifted position.

7. The combination with a support having spaced jaws one of which is formed with an aperture and the other being counterbored, a sleeve adjustably retained in said counterbored jaw against rotation and provided with an internal spiral groove, a tool standard having an external spiral groove, an axial passage and oppositely inclined radial passages connecting the axial passage with the upper and lower ends of the spiral groove of the standard, said grooves of the standard and sleeve co-acting to form a race-way and being of polygonal cross section, a continuous line of balls adapted to circulate in said race-way and passages, and means for turning said standard to raise or lower the same.

8. In a punch, a body portion, a bearing sleeve therein provided with an internal spiral groove, a tool spindle spirally movable therein and having a coacting external spiral

groove, said spindle having an axial passage and oppositely inclined radial passages connecting with the axial passage with the upper and lower ends of the spiral groove 5 of the spindle, and means for actuating said spindle.

9. The combination with a jaw; of a sleeve mounted therein and provided with an internal spiral groove, a spindle having an 10 external spiral groove cooperating with the groove of the sleeve, said spindle having a longitudinal passage and radial passages communicating with the race-way formed by the coacting grooves, and balls circulating 15 in said race-way and passages.

10. In a punch, a body portion, a bearing sleeve therein provided with an internal spiral groove, a tool spindle spirally movable therein and having a coacting external spiral 20 groove, said spindle having an axial passage and oppositely inclined radial passages connecting with the axial passage with the upper and lower ends of the spiral groove

and the spindle, a continuous line of balls adapted to circulate in said race-way and 25 passage and a plug closing said axial passage.

11. The combination with a sleeve provided with an internal spiral groove; of a working spindle having an external groove 30 cooperating therewith, an axial passage and radial passages in the upper and lower ends communicating with said grooves, the upper passage extending upwardly and outwardly and the lower passage extending down- 35 wardly and outwardly, a continuous line of balls circulating in said grooves and passages, and means for obtaining an access to said passages to apply or remove the balls.

In testimony that I claim the foregoing 40 as my own, I have hereto affixed my signature in the presence of two witnesses.
